(57) **CLAIM**

The ornamental design for a rugged overland camper trailer with convertible A-frame, as shown and described.

DESCRIPTION

FIG. 1 is a perspective view of the rugged overland camper trailer with convertible A-frame;

FIG. 2 is a first side view thereof;

FIG. 3 is a second side view thereof;

FIG. 4 is a third side view thereof;

FIG. 5 is a fourth side view thereof;

FIG. 6 is a bottom view thereof;

FIG. 7 is a top view thereof;

FIG. 8 is a second side view thereof in a first alternate position;

FIG. 9 is a second side view thereof in a second alternate position; and,

FIG. 10 is a perspective view thereof in a third alternate position.

The dotted lines depict portions that form no part of the claimed design.

1 Claim, 10 Drawing Sheets
